[57] CLAIM

The ornamental design for a shelf for potted plant stand, substantially as shown and described.

DESCRIPTION

FIG. 1 is a side elevational view of the shelf for potted plant stand showing my design, the opposite side elevational view being a mirror image of the side shown.

FIG. 2 is a front elevation view.

FIG. 3 is a bottom plan view.

FIG. 4 is a top plan view.

FIG. 5 is a rear elevational view.
